UNITED STATES PATENT OFFICE

95,377

DESIGN FOR A LAVATORY

John Richard Morgan, Oak Park, Ill., assignor to Sears, Roebuck & Company, Chicago, Ill., a corporation of New York

Application February 1, 1935, Serial No. 55,196

Term of patent 14 years

To all whom it may concern:

Be it known that I, John Richard Morgan, a subject of the King of England, residing at Oak Park, in the county of Cook and State of Illinois, have invented a new, original, and ornamental Design for a Lavatory, of which the following is a specification, reference being had to the accompanying drawing forming part thereof.

In the drawing, the figure is a perspective view of the lavatory, showing my new design.

I claim:

The ornamental design for a lavatory, substantially as shown.

JOHN RICHARD MORGAN.
